DEAD END CONNECTOR

James W. Wright, Birmingham, Mich.

Application August 12, 1941, Serial No. 406,571

6 Claims.

(Cl. 24—126)

The present invention relates to a connector device and particularly relates to a connector for the dead ends of electrical transmission cables or wires.

One of the primary objects of the present invention is to provide improvements in connectors of the type mentioned in which cables or wires may be quickly and easily attached thereto.

Another object of the invention is to provide improvements in connectors of the type mentioned in which all parts thereof may be salvaged, thereby effecting operating economies.

Another object of the present invention is to provide improvements in devices of the type mentioned which make it safer in the handling of hot primaries as compared with the old types of constructions now in use.

Other objects of the invention will become apparent from the following specification, the drawing relating thereto, and from the claims herein-after set forth.

In the drawing, in which like numerals are used to designate like parts in the several views throughout:

Figure 1 is a top plan view of a connector element embodying features of the present invention and showing such element mounted on its associated parts;

Fig. 2 is a cross-sectional view taken substantially along the line 2—2 of Figure 1;

Fig. 3 is an enlarged side elevational view of the connector element illustrated in Figure 1;

Figures 4, 5 and 6 are cross-sectional views taken substantially along the lines 4—4, 5—5 and 6—6, respectively, of Figure 3;

Fig. 7 is a fragmentary vertical cross-sectional view of one end of the connector and illustrating a modified form of that shown in Figures 1 through 6; and

Fig. 8 is a view similar to Figure 7 and showing another modified form thereof.

Referring to Figures 1 through 6 of the drawing, one embodiment of the invention is illustrated and comprises a suitable supporting element 10, which may be an ordinary crossbar or the like on a telephone or transmission pole. An insulator 12 is connected to the support 10 through a clevis 14, to which a connector 16 on the support 10 is pivotally connected by means of a pivot pin 18.

The dead end connector of the present invention is generally indicated at 20, and comprises a hollow body portion 22 having a central bore 24 formed therein. Such hollow bore is square in cross section at one end thereof, as indicated at

26, and is adapted to non-rotatably but slidably receive therein a square nut 28. The corresponding end of the body portion is provided with an opening 30 therethrough through which a bolt 32, which is fixed to the insulator 12, extends into threaded engagement with the nut 28 to fix the body 20 to the insulator 12.

The opposite end of the bore 24 is provided with a frusto conical portion 34 which opens through the opposite end thereof. A portion of the body 24 is cut away to provide an elongated opening 36 through the side wall thereof which communicates with the bore 24. A conventional cable connector 38 is receivable within the hollow interior of the body 22 through the opening 36. Such cable connector 38 is formed with frusto conical end portions, and is hollow and open at each end. In each end is received a contractible body element, and such body elements are constantly pressed outwardly in the connector 38 by means of a compression spring positioned therebetween. They are of such construction that a cable may be pushed into either end thereof, the corresponding bodies opening up against the action of the spring to permit such entrance and then, upon an outward pull being exerted upon the cable, the bodies automatically contract and clamp themselves to the cable, and, therefore, to the connector.

30 In the present case, the frusto conical end of the connector 38 is adapted to be seated in the frusto conical end 34 of the bore in the body member. The connector 38 may thus be positioned within the body member or removed therefrom through the opening 36. The body member is formed with diametrically opposed strengthening ribs 40 and 42 and with another longitudinally extending strengthening rib 44, which is positioned substantially midway between the ribs 40 and 42. Such ribs are of substantial depth, and the ribs 40 and 42 are each formed with an elongated opening 46 therein next to the body 22.

45 In the use of the construction described above, the connector 20 is suitably mounted on an insulator 12 or the like, as described above, and the cable clamp is applied to the wire 48, or the like, at a point materially outwardly from the end of the connector 20.

A block and tackle, or similar pulling device, is extended between such cable clamp and the connector 20 by fastening one end of the block and tackle through the opening or openings 46. The block and tackle is then operated to pull the cable or wire to the desired tension or sag, and wire is then cut off to a point equivalent to the

length of the forward end of the member 20 adjacent the tackle portion 30. A connector 38 is then inserted in place in the bore 24 in the position shown in Figure 2, and the end of the cable or wire is inserted into the end of the connector 38, as described above. Thereafter, the block and tackle is backed off, causing the cable or wire to be clamped by the connector 38, and then the block and tackle may be removed from the connector 20.

It will thus be seen that the connector 20, above described, provides a rugged construction and yet one in which the wire or cable 48 may be conveniently attached thereto. It will be appreciated that these are matters of considerable importance because the workman performing such a job is usually working at a bad handicap, and the convenience afforded him by the construction of the present invention is a matter of prime importance.

All parts of the dead end connector may be salvaged, inasmuch as the cable which is anchored thereby, after being cut off, may be removed from the connector 38. The main body portion 20 is capable of being applied and removed from any support and separated from the connector 38 without any damage thereto under conditions of normal handling.

It will be appreciated that it is not necessary to use the particular insulator 12 as shown, but that any suitable type of insulator or connector may be secured to the inner end of the main body portion 22. A modified form of such means is shown in Figure 7, in which the inner end of the member 20 is formed with an integral flange 50 which may be provided with a vertical pivot opening 52 therein. Such end may be connected to the insulator, or other support, by means of a clevis and pin connection such as that shown between the insulator and support in Figure 2.

Referring to Figure 8, another modified form is illustrated in which a clevis 54 is integrally formed adjacent the inner end of the member 22 and is adapted to be connected to an eye-bolt 56 by means of a pivot bolt 58.

Formal changes may be made in the specific embodiments of the invention described without departing from the spirit of the invention, the scope of which is commensurate with the appended claims.

What is claimed is:

1. A connector comprising an elongated, hollow body member having an opening through one end thereof, means providing an opening through the side wall of the member communicating with the

interior thereof, a longitudinally extending rib formed on the exterior of said member, and attachment means formed on said rib.

2. A connector comprising an elongated, hollow body member having an opening through one end thereof, means providing an opening through the side wall of the member communicating with the interior thereof, a longitudinally extending rib formed on the exterior of said member, and means providing an attachment opening in said rib.

3. A connector comprising an elongated, hollow body member having an opening through one end thereof, the interior of said member tapering inwardly toward said one end, means providing an opening through the side wall of the member communicating with the interior thereof, a longitudinally extending rib formed on the exterior of said member, and means forming an attachment opening in said rib.

4. A connector comprising an elongated, hollow body member having an opening through one end thereof, the interior of said member tapering inwardly toward said one end, means providing an opening through the side wall of the member communicating with the interior thereof, longitudinally extending ribs formed on the exterior of said member at diametrically opposed positions, and means forming attachment openings in said ribs.

5. A connector comprising an elongated, hollow body member having an opening through one end thereof, the interior of said member tapering inwardly toward said one end, connecting means formed at the opposite end of said member, means providing an opening through the side wall of the member communicating with the interior thereof, a plurality of longitudinally extending ribs formed on the exterior of said member, and means providing attachment openings in certain of said ribs.

6. A connector comprising an elongated, hollow body member having an opening through one end thereof, the interior of said member tapering inwardly toward said one end, means providing an opening through the side wall of the member communicating with the interior thereof, a connector clamping element adapted to be received within said member through said wall opening and having a surface complementary to the tapering interior of said body member, a plurality of longitudinally extending ribs formed on the exterior of said member, and means forming attachment openings in certain of said ribs.
